UNITED STATES PATENT OFFICE.

EDWIN S. PILLSBURY, OF ST. LOUIS, MISSOURI, ASSIGNOR TO CENTURY ELECTRIC COMPANY, OF ST. LOUIS, MISSOURI, A CORPORATION OF MISSOURI.

CENTRIFUGAL CIRCUIT-CHANGING DEVICE FOR ELECTRIC MOTORS.

1,157,179.

Specification of Letters Patent.

Patented Oct. 19, 1915.

Application filed February 23, 1915. Serial No. 9,986.

To all whom it may concern:

Be it known that I, EDWIN S. PILLSBURY, a citizen of the United States, residing in the city of St. Louis and State of Missouri, 5 have invented certain new and useful Improvements in Centrifugal Circuit-Changing Devices for Electric Motors, of which the following is a specification.

The principal object of my invention is to 10 provide a new and improved device for utilizing centrifugal force to change the circuits of an electric motor at a critical increase of speed.

Another object of my invention is to provide 15 a serviceable and effective stop to limit the outward movement of the centrifugal weights.

Another object is to provide pivotal connections from these weights to the other 20 mechanism so that the whole body of each weight shall move approximately radially.

Other objects are to build the centrifugal mechanism so it will occupy little space along the motor shaft and so that it can be 25 conveniently assembled.

All these objects and others will be made apparent in the following specification in which I describe one specific embodiment of my invention. It will be understood that 30 the invention is defined in the appended claims.

Referring to the accompanying drawings; Figure 1 is a longitudinal section of a motor embodying my invention. Fig. 2 is a 35 detail view looking in the direction of the arrow 2 in Fig. 7. Fig. 3 is a detail section on the line 3 of Fig. 6. Fig. 4 is a section the same as for the corresponding part of Fig. 1 but with the shaft removed. Fig. 5 40 is an elevation of the parts of Fig. 4 as viewed from the right. Figs. 6 and 7 correspond respectively with Figs. 4 and 5 but showing the centrifugal weights displaced.

As shown in the drawings, the motor 45 comprises the stator laminations 15 and the rotor laminations 16 fixed on the shaft 17. The commutator segments 18 are arranged radially so that the commutator surface is a plane transverse to the shaft 17. The 50 brushes 19 normally press against the commutator but may be released by pushing to the left, as viewed in Fig. 1, on the members 20 carried by the parallel motion links 21. The sleeve 22 around the shaft 17 car-

ries a circumferential series of short circuiting members 23, and centrifugal force causes them to press against the ring 24. When the sleeve 22 is pushed to the left, as viewed in Fig. 1, the members 23 connect the inner ends 25 of the commutator segments 18 to the ring 24, thus short circuiting the rotor coils. The sleeve 22 is fixed at its end on the ring 28 and a spring 26 acting between the ring 28 and abutment 27 on shaft 17, keeps the members 23 normally in 65 the position shown in Fig. 1.

The ring 28 carries two pins 29 with sockets 30 which receive the ends of the rods 31 extending through slots 60 in the rotor 16.

The shaft 17 has fixed thereon a shoulder 70 32 against which rests a flange 33 forming an abutment at one end of the rotor laminations 16. At the other end is an annular cup with its base 35 against the laminations 16. The outer wall 34 of this cup is a cylindrical shell and the inner wall 37 fits around the shaft 17 and has its edge 39 crimped in the groove 38 around said shaft. Holes 36 are provided through the base 35 to accommodate the rods 31. 80

Within the shell 34 is a channel collar 40. From its outer flange on opposite sides there project two spring tongues 41 with outward ends 42 that enter holes 43 in shell 34 and thus keep the collar 40 in place in shell 85 34. The lugs 44 may be engaged to remove the spring tongues 41, when the parts are disposed as in Fig. 7, and it is desired to remove collar 40.

From the inner flanges of the collar 40, 90 on opposite sides, there project two lugs 45 to which are connected the ends 47 of the bell-crank yokes 46 by means of the pivot pins 48. Each yoke 46 has a socket 49 at its middle point engaging the ball 50 on the end 95 of the corresponding rod 31. On each side each yoke 46 carries an arm 51 with its end attached by the pivot pin 55 to one side of the half shell 52. There are two of these half shells 52, and each of them carries 100 tongues 57 which project through corresponding holes in a segment 56 and have their ends headed over so as to secure the parts 52 and 56 rigidly together. A half-shell 52 and its connected segment 56 constitute a centrifugal weight and there are 105 two such weights. Each half-shell 52 is notched at 53 to accommodate the ball and

socket joint 49—50 (see Fig. 4), and likewise notched at 54 to accommodate one end of arm 51 of yoke or bell-crank 46.

The segments 56 have the shape shown in Figs. 5 and 7. Each segment is cut away at one side at 58 and the other segment is extended at 59 to enter this cut-away place, as in Fig. 5. The object of this is to bring the center of mass of each centrifugal weight 52—56 closer to shaft 17; or otherwise expressed, to carry part of each weight 52—56, namely the part 59, past the axis of the shaft 17 so that its centrifugal force will act oppositely to the major portion of the weight 52—56 when in the position of Fig. 5, but therewith when in the position of Fig. 7. Thus when the weights 52—56 fly out by centrifugal force, they become increasingly effective to overcome the resistance of the spring 26.

When the motor is at rest the parts have the positions shown in Figs. 1, 4 and 5. When a single phase alternating current is applied the motor starts as a commutator motor. After a certain speed has been attained, the centrifugal weights 52—56 fly out until the half-shells 52 strike the inside face of the shell 34, which acts as a stop. By this movement the bell-crank yokes 46 are carried from the position of Fig. 4 to that of Fig. 6, and push on the rods 31, and thereby shift the sleeve 22 and the short-circuiting members 23 so as to connect the commutator segments 18 to the ring 24 and thus short circuit the rotor coils. At the same time the end of the sleeve 22 pushes the members 20 and releases the brushes 19. Thereafter the motor runs as an induction motor. At slowing down and stopping the reverse operations occur as will be obvious.

The weights 52—56 move in a radial plane and substantially in a radial direction and each weight has no stationary pivot but its pivot and its whole mass move all alike and with utmost effect, whereas if each weight had some part on a pivot fixed on the shaft 17, the part adjacent to such pivot would be ineffective. The centrifugal device is easy to manufacture, being made of sheet-metal punchings throughout, and it is easy to assemble, for the collar 40, yokes 46, rods 31 and weights 52—56 can be assembled, then the rods 31 thrust through the holes 36 into the sockets 30, the collar 40 slipping within the shell 34 and the ends 42 of the tongues 41 snapping into the holes 43 in the shell 34. Thus the whole governor mechanism can be assembled as a unit and instantly applied to or detached from the rotor. The arrangement of the parts, and particularly the flat segments 56, cause the centrifugal mechanism to occupy very little longitudinal space on the shaft 17. The stops 34 to engage the half-shells 52 give large wearing surface and strength and ri-

gidity. There are no pivotal joints subjected to twisting strains. By actual trial in the testing room I have caused a motor constructed in accordance with this specification to make over one hundred thousand 70 starts and thereafter it showed no appreciable wear on the parts of the centrifugal mechanism.

I claim:

1. In combination, a stator, a shaft journaled therein, a rotor on said shaft, a circuit-changing member carried by said shaft and adapted to slide longitudinally thereon, levers pivoted on the shaft and connected to said circuit-changing member, and centrifugal weights pivotally connected to said levers.

2. In combination, a stator, a shaft journaled therein, a rotor on said shaft, a circuit-changing member carried by said shaft and adapted to slide longitudinally thereon, a pair of opposite bell-cranks fulcrumed on said shaft with a common plane of movement containing the axis of the shaft, a pair of weights pivotally attached to corresponding ends of respective bell-cranks, and rods connecting the remaining ends of said bell-cranks to said circuit-changing member.

3. In combination, a stator, a shaft journaled therein, a rotor on said shaft, a circuit-changing member carried by said shaft and adapted to slide longitudinally thereon, a pair of bell-cranks fulcrumed on said shaft with a common fulcrum axis at a right angle with the axis of the shaft and in the same 100 plane therewith, a pair of weights pivotally attached to corresponding ends of the respective bell-cranks, and rods connecting the remaining ends of said bell-cranks to said circuit-changing member.

4. In combination, a stator, a shaft journaled therein, a rotor on said shaft, a circuit-changing member carried by said shaft and adapted to slide longitudinally thereon, a pair of bell-crank yokes on opposite sides 110 of the shaft and pivoted at their ends on pins fixed relatively to the shaft, the axis of these pivots for each bell-crank intersecting the shaft at a right angle to its axis, a pair of weights pivotally attached to corresponding ends of the respective bell-cranks, and rods connecting the remaining ends of said bell-cranks to said circuit-changing member.

5. In combination, a stator, a shaft journaled therein, a rotor on said shaft, a circuit-changing member carried by said shaft and adapted to slide longitudinally thereon, a cylindrical shell fixed on said shaft at one end of the rotor, mechanism comprising centrifugal weights adapted to fasten in said shell and an operative connection from said mechanism to said circuit changing member.

6. In combination, a stator, a shaft journaled therein, a rotor on said shaft, a circuit

- changing member carried by said shaft and adapted to slide longitudinally thereon, a cylindrical shell fixed on said shaft at one end of the rotor, mechanism comprising centrifugal weights adapted to fasten in said shell and an operative connection from said mechanism to said circuit changing member, said shell being adapted to act as a stop for said weights.
- 5 7. In combination, a stator, a shaft journaled therein, a rotor on said shaft, a circuit changing member carried by said shaft and adapted to slide longitudinally thereon, a cylindrical shell fixed on said shaft at one end of the rotor, a collar adapted to fit in said shell, means to fasten said collar detachably therein, mechanism comprising centrifugal weights carried by said collar, and an operative connection from said mechanism to said circuit changing member.
- 10 8. In combination, a stator, a shaft journaled therein, a rotor on said shaft, a circuit changing member carried by said shaft and adapted to slide longitudinally thereon, a cylindrical shell fixed on said shaft at one end of the rotor, a collar to fit in said shell, said shell having holes therethrough, spring tongues carried by said collar adapted to snap in said holes, mechanism comprising centrifugal weights carried by said collar and an operative connection from said mechanism to said circuit changing member.
- 15 9. In combination, a stator, a shaft journaled therein, a rotor on said shaft, a circuit changing member carried by said shaft and adapted to slide longitudinally thereon, a cylindrical shell fixed on said shaft at one end of the rotor, mechanism comprising centrifugal weights adapted to fit within said shell, each centrifugal weight consisting of a half-shell within said cylindrical shell and a segment attached thereto extending across the end edge of the cylindrical shell, and an operative connection from said mechanism to said circuit changing member.
- 20 10. In combination, a stator, a shaft journaled therein, a rotor on said shaft, a circuit changing member carried by said shaft and adapted to slide longitudinally thereon, said shaft having a groove around it, an annular cup around said shaft with its base against one end of the rotor and its inner flange engaging said groove, mechanism comprising centrifugal weights adapted to fasten in said cup, and an operative connection from said mechanism to said circuit changing member, said shell being adapted to act as a stop for said weights.
- 25 11. In testimony whereof, I have subscribed my name.
